UNITED STATES PATENT OFFICE.

LESTER SIEBERT, OF SAN FRANCISCO, CALIFORNIA.

SAFETY-SWITCH MECHANISM.

Application filed May 19, 1919. Serial No. 298,116.

To all whom it may concern:

Be it known that I, LESTER SIEBERT, a citizen of the United States, residing at the city and county of San Francisco, and State of California, have invented certain new and useful Improvements in Safety-Switch Mechanism, of which the following is a specification.

The present invention relates particularly to improvements in protecting means for knife blade or lever switches, and has for its principal objects to provide a construction whereby when the switch member is in closed position accidental contact with the conducting portions thereof is prevented, and likewise when the same is in opened position accidental contact with the live element with which the movable switch member contacts is prevented, thus providing a construction by the use of which the live elements of knife blade or lever type switches are effectively protected against accidental contact by those who operate the same. A further object is to provide a construction for protecting the live points or ends of the fuse elements generally associated with switches of this type and to prevent contact therewith during such time as the switch elements are operated and to provide a construction wherein the switch element or elements together with the fuse element or elements are encased or enclosed and the respective elements are exposed to operation through the opening of separate doors or closures, whereby it is impossible to obtain access to the fuse element during such time as the door or closure to permit the operation of the switch element is open.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Fig. 1 is a view in elevation of the preferred embodiment of my invention with the switch enclosing door in open position en-

abling the operation of the switches within the box.

Fig. 2 is a transverse sectional view taken on line 4—4 of Fig. 1, but with the switch enclosing door in closed position and one of the switch members in open position. Fig. 3 illustrates a switch provided with a plate for protecting the live contact.

Referring more particularly to the drawings, wherein like characters of reference designate corresponding parts, the numeral 1 indicates a suitable switch box having a hinged cover plate 2 capable of being open to permit access to the entire interior of the box, and when in closed position, preferably retained from being opened by screws or other removal fastening means 3.

Mounted within the box, in any suitable manner, as on the supports 4, is a conventional board or plate 5 preferably of insulating material, and which carries the conducting means and switch elements together with the fuse connecting elements, hereinafter described.

Surrounding the board or plate are the side members 6 which extend to a point approximately level with the box side walls, as illustrated in Fig. 4.

The box cover 2 is provided preferably in its center with an opening 7 normally closed by the fuse enclosing door 8 hinged to the cover 2, as at 9, said door being in turn provided approximately in its center with the outstanding annular flange 10 which forms the side walls of an opening 11 in said door, and through which opening, when the door 8 is closed, access may be had to the switch elements. This door 8 is preferably precluded from being opened by unauthorized persons by the use of a lock member 12 carried thereby and the latch of which is adapted to project beyond the inner surface of the cover door 2, as in Fig. 4 of the drawings. The opening 11 in the member 8 is capable of being closed through the operation of the switch enclosing door 13 hinged preferably as at 14 to the flange 10 surrounding the opening and retained in closed position by any suitable form of locking means 15.

While in the drawings I have illustrated four switches and their associated coating parts, the same forming a switch board unit, it is thought that a description of one of these units and its associated elements will suffice, and it is to be understood that one or more of the switches and associated elements

may be employed in any construction, and that under certain conditions the box or enclosing casing may be dispensed with, if it is so desired.

5 Carried at the rear of the board or plate 5 are the bus bars 16, illustrated as three in number, and the same are connected through any suitable means with a source of power, said source of power preferably entering 10 the box 1 from an exterior point and connected with the bus bars at a point immediately below the removable plate 17, Figs. 2 and 3 of the drawings.

Passing through the plate 5 and one or 15 more associated with each switch mechanism, are the live terminal points 18 of any well known construction, said points lying preferably below the opening 11. A switch 19 having an operating handle 20 and 20 of the commonly termed knife blade or lever type is illustrated as being movable on its pivot 21 to connect the terminals 18 with the distributing lines controlled by said switch.

25 As illustrated in the drawings, the upper exposed portion of the switch bar 19 is protected by a cover plate 22 from accidental contact by the operator, said plate being movable with the switch element in its 30 movement to and from the board 5 and is constructed either of conducting material insulated from the bar 19 or of non-conducting material in contact with or insulated from the bar 19, the area of said plate being 35 sufficient to overlie said bar, and when the switch is in closed position to project a slight distance rearwardly from the fulcrum point 21.

In some constructions it is desirable to 40 position fuses within the switch box for protecting the distributing lines, and in the present case the members which yieldably engage the ends of the fuses are illustrated particularly in Fig. 4, one being associated 45 through a conducting member 23 extended from the fulcrum point 21 and resting on the upper surface of the plate 5. These spring members may be of any suitable construction just so long as the same are capable 50 of receiving the conducting terminals of a fuse, and the fingers 24 for engaging and retaining any given fuse in position are spaced from each other and are only conductively connected through the fuses 25; 55 preferably of any approved type, particularly illustrated in Fig. 3 of the drawings. From one of the two contact fingers 24 of each pair associated with the respective fuses extends a distributing wire or lead 60 25², the circuit through which is controlled by the operation of the switch blade 19.

The spring contact fingers 24 are also protected from accidental contact through the protecting plates 25 and 26, the plate 65 25 being hinged as at 27 to the rear edge

of the plate 22 overlying the switch bar 19 and on the opening of the switch, as in Fig. 4 of the drawings, said plate is maintained in contact and rides on the spring finger which it overlies or rides on the end 70 of the fuse received in the spring finger by the action of a coiled spring 28 secured at one end to the underside of the plate 25 and at its opposite end to the underside of the plate 22. 75

Thus the fuse end adjacent the switch end is at all times protected when the switch is in either open or closed position. The present construction enables the employment of the exposed terminal fuses now universally in use and likewise the use of the conventional and inexpensive knife blade or lever switches now in universal use and provides a covering for the live elements of the switch and fuse when the switch is in either 80 open or closed position. The plate 26 overlying the other spring contact finger of any given pair is hinged as at 29 to the wall 6 and is normally held in the position to overlie its associated contact finger by a suitable 85 coiled spring 30.

It will be apparent from an examination of the drawings that the respective switches are positioned within the box, to lie with their fulcrumed points substantially in 90 alignment with the edge of the opening 11 so that the opening of the door 13 will permit access to be had to the switches to operate the same, but will preclude access being had to the switch fuses. 95

As the switch fuses are only renewed by authorized persons, and in some cases by persons different from those who merely open and close the switches, access is precluded therefrom until such time as the authorized person opens the door 8, which in turn carries the door 13, at which time access may be had to either renew the fuses or to operate the switches. 100

While in Figs. 1 to 4 of the drawings no 110 means is provided for preventing accidental contact with the live terminal 18 of the respective switches, when the switch is in open position, it is readily apparent that a plate 31 similar to the plate 25 may be pivotally 115 connected as at 32 to the free end of the blade 19, it being normally forced into contact with the surface of the board 5 to ride thereon through the action of a spring 33, this construction being illustrated in Fig. 5 120 of the drawings.

By my improved construction I am enabled to provide a switch of the knife blade or lever type which when in closed or opened position is provided with means for 125 preventing accidental contact with live or charged portions thereof, and by the providing of an improved box construction the opening of the door 13 only permits access to be had to the movable switch members, 130

overcoming all liability of the operator touching any exposed portions of the conducting members, either when making or breaking the circuit controlled by said 5 switch or switches where a number of independent units are employed.

By my present invention it is possible to protect the live portions of the inexpensive type of knife blade or lever switch from 10 accidental contact by the operator, enabling said switches to be used where the rotary type of protected switch is now employed.

Having thus described my invention, what I claim as new and desire to protect 15 by Letters Patent is:—

1. In combination with a movable switch of the knife or lever type a base mounting the same and to and from which said switch is movable, a pair of terminals disposed in 20 the same plane and adapted for connection by said switch when the same is in closed position, a cover plate overlying said movable member and movable therewith to overlie said movable contact and terminals 25 to protect the same from accidental contact when the switch is in closed position, and a hinged member adapted to overlie the live one of said terminals on the disengagement of the movable contact therefrom, to 30 preclude accidental contact with said live terminal when the movable switch is disengaged from one of said terminals.

2. In combination with a movable switch of the knife or lever type, a base mounting 35 the same and to and from which said switch is movable, a pair of terminals adapted for connection by said switch when the same is in closed position, a cover plate overlying said movable member and movable there- 40 with to overlie said movable contact and terminals to protect the same from accidental contact when the switch is in closed position, and a member hinged to the said movable contact for movement therewith and adapt- 45 ed to overlie the live one of said terminals on the disengagement of the movable con-

tact therefrom to preclude accidental contact therewith.

3. In combination with a switch of the knife or lever type and associated contacts, 50 of means mounted on and movable with the switch for precluding accidental contact with the conducting portions thereof or of said switch contacts when the switch is either in closed or opened position. 55

4. In combination with a pivoted knife or lever switch and its associated contacts connected thereby, a pair of exposed fuse contacts associated with said switch, a cover plate carried by the switch member and 60 movable therewith for precluding accidental contact with the switch conducting portions and its associated contacts, and a pivotally mounted protecting plate for said fuse contacts to overlie and cover the same to preclude accidental contact with the conducting portions thereof, said plate being capable of 65 pivotal movement independent of said cover plate.

5. In combination with a lever switch 70 pivotally mounted at one end, a normally energized jaw contact engageable thereby, and means carried by the switch for precluding accidental contact with the conducting portions thereof or with said jaw when said switch is either in closed or opened position. 75

6. In combination with a base, a pivoted lever switch carried thereby, a normally energized jaw contact engageable thereby, and a movable member associated with said jaw 80 contact and operated by the movement of said switch to overlie said jaw contact on the disengagement of the switch therefrom to preclude accidental contact with said jaw contact. 85

In testimony whereof I have signed my name to this specification in the presence of two subscribing witnesses.

LESTER SIEBERT.
